FOWL SUSPENSION APPARATUS

Lenus Jasper, Orland, Calif., assignor to
Seth S. Barker, Ottumwa, Iowa

Application November 13, 1940, Serial No. 365,439

5 Claims. (Cl. 17—44.1)

1

My invention relates to the plucking of fowl, and more particularly to apparatus for accomplishing such result.

Among the objects of my invention are:

- (1) To provide novel and improved apparatus for suspending fowl in a plucking operation;
- (2) To provide novel and improved apparatus for the plucking of fowl, which shall be fast and economical in operation; and
- (3) To provide novel and improved apparatus for suspending fowl, which shall be adaptable to the handling of birds of various sizes.

Additional objects of my invention will be brought out in the following description of the same taken in conjunction with the accompanying drawings wherein—

Figure 1 is an elevational view of a fowl suspension frame;

Figure 2 is a view in section through the means for supporting the frame of Figure 1;

Figure 3 is a view in section of the same supporting means taken at right angles to that of Figure 2;

Figure 4 is a sectional view along the line 4—4 of Figure 2;

Figure 5 is a fragmentary view, showing the means by which the fowl suspension frame of Figures 2 and 3 can be rotated;

Figure 6 is an enlarged sectional view along the line 6—6 of Figure 1;

Figure 7 is a view illustrating a wing clamp carried on the fowl frame of Figure 1;

Figure 8 is an enlarged view of the head grip also carried on the fowl frame of Figure 1; and

Figure 9 is an enlarged view of a locking means for the fowl frame of Figure 1.

My invention relates to a suspension means for use in a process in which the removal of feathers from fowl is accomplished by subjecting the bird to a sustained flow of fluid, preferably water, at high velocity sufficient to effect removal of the feathers therefrom. The invention, preferably, involves some preliminary step to facilitate the removal of the feathers in this manner. For example, in preparation for the removal of the feathers, I prefer to treat the bird in a manner to relax and soften the feather follicles, and this may be accomplished in any suitable manner, such as exposing the bird to a bath of hot water, though I prefer to utilize the same apparatus which directs the high velocity fluid against the body of the bird to effect removal of the feathers, and thereby effect economies in both time and cost. In using this apparatus to perform this preliminary step, I direct against the bird a stream of

2

liquid, such as water, at high temperature but at a reduced pressure, and continue the same for a brief period of time sufficient to accomplish the desired relaxing and softening of the feather follicles. The apparatus is arranged so that both the preliminary step and the final step of removing the feathers are accomplished most efficiently in sequentially timed operations. Practically all the feathers may thus be removed, except for possibly some of the more strongly embedded tail and wing feathers which may subsequently and conveniently be plucked by hand.

The frame for suspending the fowl in such a plucking process is indicated at 25 and is designed to follow the general contour of a bird 27 with its wings outstretched. The frame includes an upper, substantially rectangular section 29, a lower section 31 of V-shape, and oppositely directed intermediate wing sections 33. The upper, substantially rectangular portion includes a pair of horizontally disposed bars 35 anchored to a suspension cylinder 37 adjacent a closed end thereof. The vertical sections 39 of this rectangular portion are hinged at the extremities of the horizontal bars 35 and joined to the wing portions 33 of the frame.

The V-shaped portion 31 terminates at its apex in a vertically disposed tube 41. One side of the V-shaped portion is split, enabling both sides of the frame to swing on their respective hinges, and spreading of the frame, in the absence of any restraining force, is assured by spreading means disposed in each of the corners of the rectangular portion of the frame. Each of such spreading means comprises a compression spring 43 disposed about a rod 45 which is hinged to the vertical side member 39 of the rectangular section, and passes through a lug 47 depending from the adjacent horizontal bar 35. The frame may be retained against such spreading, when in use, by means of a locking tube 49 disposed about one end of the split portion, and having a longitudinal slot therein to receive a guide pin 53.

Telescopically disposed about the suspension cylinder 37, is another cylinder 55 to which are attached a pair of leg clamps 57. Each of such leg clamps includes a strip 59 of metal pivotally secured at the upper portion of its supporting cylinder. This strip is bent at an intermediate point, to provide an angularly disposed section 61 and an adjoining end section 63. The first section 61 is provided with a slot 65 adjacent the bend, while the end section is formed with a notch 67 in one edge thereof of a size sufficient to conveniently receive the leg of a fowl, and yet small

enough to preclude passage of the foot of the bird therethrough.

A second element of the clamp comprises a straight strip 69 of metal pivotally secured to the clamp supporting cylinder 55 at a point below the point of attachment of the first member 59, and slidably passing through the slot 65. The length of this second member is sufficient to extend across the notch 67, while its width at that point is insufficient to cover the notch entirely. This condition obtains when the clamp elements are in a condition of stable equilibrium.

The telescopic arrangement of the two cylinders 37 and 55 permits of adjusting the position of the leg clamps with respect to the lower portion of the fowl frame. Such adjustment is realized by providing the suspension cylinder 37 with a longitudinal slot 71, and backing the same up with a heavy strip 73 of metal having a corresponding slot 75 in alignment therewith, together with lateral notches 77 extending therefrom. The clamp supporting cylinder 55 is perforated adjacent its upper edge to receive a spring biased pin 79 terminating at its inside end, in a button 81. This pin extends through the slots 71 and 75, and the button 81 is adapted to enter any one of the plurality of lateral notches 77 which have been formed in the backing strip 73. The positioning of the button in any of these lateral notches will determine the elevational position of the leg clamps.

In each of the wing portions of the frame, there is disposed a wing clamp 83. This comprises a pair of cooperating jaws 85 and 87, each of which is preferably rubber-lined, the jaws being pivotally connected asymmetrical with reference to the bisector of the jaw angle by a rivet 89. One of these jaw members 87 is formed with an integral handle member 91 which extends through a supporting bearing 93 mounted at the extremity of the wing section, and which constitutes the support for the wing clamp. The other jaw member has pivotally secured thereto, a handle member 95 which is provided with an offset 97 in the direction of the other handle member 91. A link 99 connects this offset with the extremity of an adjusting screw 101, such adjusting screw passing through a lateral lug 103 formed on the handle member 91. A spring 105 connecting between the jaw member 85 and the handle member 91, tends to bias the two jaw members to open position. The dimensions of the respective parts and their specific arrangement are such as to bring about a toggle action in the operation of the clamp, so that the jaw members may be clamped in closed position or sprung to open position merely by closing or spreading the handle components. The link 99 is provided with a lug or stop 107 to determine the limit of throw of the handle member 95 in the closing direction.

A spring 109 extending about the protruding end of the handle member 91 and in compression against a blocking nut 111, tends to pull the wing clamp 83 toward the extremity of the wing portion of the frame.

In the tube 41 at the apex of the V-section of the frame, there is disposed a spring 113 anchored to an adjustable block 115 in the lower portion of the tube. The upper end of the spring connects to a spool 117 under tension. The spool spans the upper end of the tube and carries a hook 119. This mechanism constitutes a head

grip for engaging the head of a fowl when a fowl is suspended in the frame.

The fowl frame is adapted to be pivotally suspended from special links 21 incorporated in a conveyor chain travelling past a point where the plucking process is to take place. Such suspension means is best disclosed in Figures 2 and 3 of the drawings. It includes a plurality of studs 121 disposed about the periphery of the closed end of the suspension cylinder 37. Each of the studs has a roller 123 disposed about it, and these are held in position by a circular disk or plate 125 carried by the studs. A pivot pin 127 connects this disk at its center to the lug 23 forming a part of the special carrying link 21 previously mentioned. About this pin there is positioned a bearing 129 which has integrally extending therefrom in an upward direction, a bracket 131 for receiving a track roller 133. This roller is adapted to engage and ride upon a track 19 supported above the conveyor chain.

In suspending a fowl in the frame, the legs are first positioned in the leg clamps, and this is very readily accomplished with my improved clamping device, merely by lifting up on the clamp forming members, which causes the straight strip element 69 to partially withdraw through the slot 65 and expose the notch 67 in the edge of the end section, whereupon the leg of the bird might be slipped into position and locked therein, merely by permitting the weight of the bird to restore the clamp elements to their initial state of equilibrium.

The head of the bird may be fixed against swinging or other movement, by engaging the hook 119 in the lower mandible of the bird, against the tensioning effect of the spring 113. One of the wings may then be gripped by one of the wing clamps 83, and similarly the second wing may be gripped by the other wing clamp, the springs 109 associated with these clamps tending to tension the wings and hold them in outstretched position.

During the travel of the fowl frame around the conveyor with a bird suspended therein, the bird is exposed to, first, the preliminary treatment for relaxing and softening the feather follicles, and secondly, to the feather removal treatment. For the purpose of applying fluid to the fowl both for the preliminary treatment and the plucking treatment, pipes 149 are provided. The pipes 149 are shaped to follow generally the contour of the frame 25 and of the fowl, and are provided with nozzles 151 for directing fluid onto the fowl. Convenient means is provided for supplying the fluid of the temperatures and under the pressures desired in the proper sequence.

It is of course desired that the fowl be subjected on all sides to the treatments above referred to, and for this purpose I provide a means for turning the frame 25 as it passes by the treatment station. A rack 181 is supported along the line of travel of the frame 25 at the point of treatment, and so positioned as to engage the rollers 123 on the fowl frame and cause a slow turning movement of the frame.

It will thus be apparent from the above description of my invention, that the objects as set forth by me are fully realized. While I have disclosed my invention in great detail, it will be apparent that the same may be subject to modification and alteration, without departing from the spirit thereof, and I, therefore, do not desire to be limited in my protection to the details dis-

closed and described, except as may be necessitated by the appended claims.

I claim:

1. Fowl suspension means comprising a hanging support, an angularly formed strip hingedly secured to said support and including an end portion having a notch extending into a side edge thereof, said notch being of a size to receive at least one leg of a fowl, and a second strip hingedly secured to said support below the first strip and slidably engaging said first strip at the junction of said end portion with the remainder of said first strip, said second strip having a length sufficient to extend across the notch in said end portion when the strips are in one position of their movement on their hinges.

2. Fowl suspension means comprising a hanging support, an angularly formed strip hingedly secured to said support and including an end portion having a notch extending into a side edge thereof, said notch being of a size to receive at least one leg of a fowl, and a second strip hingedly secured to said support below the first strip and slidably extending through said first strip at the junction of said end portion with the remainder of said first strip, said second strip having a length sufficient to extend across the notch in said end portion when the strips are in one position.

3. Fowl suspension means comprising a hanging support, an angularly formed strip hingedly secured to said support and including an end portion having a notch extending into a side edge thereof, said notch being of a size to receive at least one leg of a fowl, and a second strip hingedly secured to said support below the first strip and slidably extending through said first strip at the junction of said end portion with the remainder

of said first strip, said second strip having a length sufficient to extend across the notch in said end portion when the strips are in one position, and a width at its notch crossing portion substantially less than the depth of said notch.

5 4. Fowl suspension apparatus comprising a frame adapted to surround the body of a bird to be suspended, including a substantially rectangular upper section to accommodate the rear portion of such bird, a lower section of V-shape to accommodate the front portion of such bird and a pair of oppositely extending wing accommodating sections intermediate said rectangular section and said V-shape section.

10 15 5. Fowl suspension apparatus comprising a frame including a substantially rectangular section at one end thereof, a section of V-shape at the opposite end thereof and oppositely extending wing sections intermediate said rectangular section and said V-shape section; a pair of leg grips disposed in said rectangular section; a head grip in said V-shape section, and grip means in each of said wing sections for holding the wings of a fowl in outstretched condition.
